PALLET OF THE LOAD TRANSFER TYPE

Oscar F. Arthur, Connellsville, Pa.

Application April 17, 1947, Serial No. 741,983

5 Claims. (Cl. 248—120)

1

My invention relates to pallets such as those that are transportable by fork-lifting trucks and are adapted for carrying loads either for transportation or for stacking in storage or in freight cars. More specifically, the invention relates to that type of pallet known as the transfer platform type wherein the load can be removed from the pallet by a fork-lifting truck, without moving the pallet.

One example of the utility of pallets of the transfer platform type is that large pallets with heavy loads of merchandise can be transported to a shipping platform and the loads transferred piece-meal therefrom, by lifting trucks, to pallets that are small enough to permit delivery thereof into a freight car or a warehouse which does not have doorways or passageways large enough to accommodate the larger pallets.

My invention has for its object the provision of a pallet of a transfer platform type that may be made entirely or mainly of heavy gauge wire and which is of great strength for a given weight of material.

In the accompanying drawings, Figure 1 is a perspective view of the pallet structure; Fig. 2 is an end view thereof; Fig. 3 is a side view; Fig. 4 is a view taken on the line IV—IV of Fig. 1; Fig. 5 is a view taken on the line V—V of Fig. 1; Fig. 6 is a bottom plan view of the structure of Fig. 1, with various of the elements omitted, to show various of the parts with greater clarity, and Figs. 7 and 8 are perspective views showing the forms of guard plates employed to prevent damage by the forks of lifting trucks to various of the leg elements of the structure.

The pallet has a deck having deck areas at A and B, the areas B being spaced from the wider area A to permit of vertical movement of lifting forks through these spaces when lifting a load from the deck, as will be hereinafter described. The deck area A is of mesh form and comprises wires 10 welded together to form a mesh strip or sheet. Heavier wires 11 that extend longitudinally of the deck are welded to transverse wires 12 at the ends of the strip. The wires 10 may suitably be of No. 2 gauge while the wires 11—12 may be of No. 0 gauge to reinforce and stiffen the lighter mesh 10. Similarly, the strips B will be formed of lighter mesh wires 13 with marginal heavy wires 14 and 15 welded thereto at the edges and ends.

The underframe or base for the deck sheets may suitably be made mainly of 0 gauge wire and comprises a pair of longitudinally-extending floor wires or rods 17 adjacent to each longitu-

2

dinal edge of the pallet structure and two longitudinal pairs of floor rods 18 near the middle of the pallet. The ends of the floor bars 17—18 are bent upwardly at their extremities and welded to the deck sheets A—B, as shown more clearly in Figs. 2, 3 and 5. Floor plates 19 and 20 are welded to the rods 18 and to the inner rods 17, to provide a wider-faced bearing surface on the base to facilitate stacking of the pallet on other pallets, as well as to give some stiffening and strength to the structure. The plates are ribbed as shown more clearly in Fig. 2 and are deflected upwardly where they overlie the rods 17—18, the lower surfaces of the plates being mainly flush with the bottom planes of the rods 17—18.

Leg elements 23 of generally U-shape have their legs welded to the deck sheets at various points throughout the structure to afford vertical support for the deck. These legs variously overlap and are welded to the floor rods 17—18. Tie rods 24 (Figs. 2 and 3) extend transversely of the pallet and are welded to the legs 23 at a plane approximately mid way between the upper and lower ends of the legs. Longitudinally-extending rods 25 and 26 (Figs. 1 and 6) are welded to the undersurfaces of the legs 23, between the floor rods 17 and 18 respectively. Additional leg elements 27 of U-form are located between the leg elements 23 at the longitudinal edges of the pallet, as shown more clearly in Figs. 1 and 3, in order to provide greater strength at such edges.

Brace rods 28 are welded to the floor rods 17, at their ends, and have their mid portions deflected upwardly and welded to the deck sheet A, as shown more clearly in Figs. 2 and 4.

In order to prevent damage to the vertical wires by the forks of lifting trucks, sheet metal guard plates 31 and 32 are welded to the legs at the points where the lifting forks will enter beneath the deck or beneath the load that is on the deck.

When the pallet, together with its load, is to be transported, the forks of a lifting truck can be entered from the longitudinal edges of the truck, through openings C (Fig. 3) into position beneath the deck, from either side of the pallet, in order to transport the pallet and any load contained thereon. When it is desired to lift the loading from the pallet, the lifting forks will be entered from either end of the pallet into the openings or channel-like spaces D (Fig. 2), above the tie rods 24, the vertical space between these rods and the deck sheets being sufficient to receive the forks. The load can thereby be lifted from the pallet.

3

I claim as my invention:

1. A pallet having load-receiving areas that are formed by deck portions that are spaced laterally of one another, to provide openings through which lifting forks can enter horizontally and be raised and lowered, to planes above and below said areas, leg members for supporting the deck members, and transversely-extending tie bars connecting the leg members at a plane below that at which lifting forks can enter beneath lading carried by said areas.

2. A pallet having load-receiving areas that are formed by deck portions that are spaced laterally of one another, to provide openings through which lifting forks can enter horizontally and be raised and lowered, to planes above and below said area, leg members arranged in rows parallel to the said deck portions and laterally thereof, for supporting the deck members, the leg members in each row being spaced apart to permit the movement of lifting forks horizontally into said openings and beneath the deck portions, from another horizontal direction, and tie members extending transversely of the said openings and connecting the leg members of one row with those of another row, at a plane below that at which lifting forks can enter beneath lading carried by said areas.

3. A pallet having load-receiving areas that are formed by deck portions that are spaced laterally of one another, to provide openings through which lifting forks can enter horizontally and be raised and lowered, to planes above and below said areas, leg members arranged in rows parallel to the said deck portions and in rows laterally thereof, for supporting the deck members, the leg members being spaced apart to permit the movement of lifting forks horizontally into said openings and beneath the deck portions, from another horizontal direction, tie members extending transversely of the deck portions and connecting the leg members of the first-named rows at a plane below that at which lifting forks can enter

beneath lading carried by said areas, and other tie members extending parallel to said deck portions and connecting the lower ends of the legs, at a plane below the first-named tie members, whereby lifting forks may be entered horizontally above the said other tie members and be engaged beneath the said deck portions.

4. A pallet having three deck portions of lattice form that are spaced laterally of one another to provide spaces for the vertical movement of lifting forks, to planes above and below the deck surface, a plurality of leg elements for supporting each deck portion and spaced longitudinally thereof, tie members connecting the legs of each deck portion to the legs of other deck portions, at a plane approximately mid-way between the uppermost and lowermost planes of the pallet structure, and diagonally-extending brace rods connecting the intermediate deck portion to the lower ends of the legs of the outer deck portions.

5. A pallet having load-receiving areas that are formed by deck portions that are spaced laterally of one another, to provide openings through which lifting forks can enter horizontally and be raised and lowered, to planes above and below said areas, leg members for supporting the deck members, tie bars connecting the lower ends of the legs, and tie rods extending transversely of the load-receiving areas at a plane approximately midway between the uppermost and lowermost planes of the structure and being secured to the legs.

OSCAR F. ARTHUR.
